UNITED STATES PATENT OFFICE.

GEORGE G. ERDOS, OF BROOKLYN, NEW YORK, ASSIGNOR TO INDEPENDENT PAPER MILLS INC., OF BROOKLYN, NEW YORK, A CORPORATION OF NEW YORK.

DISPENSER FOR NAPKINS AND THE LIKE.

Application filed April 14, 1923. Serial No. 631,991.

To all whom it may concern:

Be it known that I, GEORGE G. ERDOS, a citizen of Hungary, residing in the borough of Brooklyn, county of Kings, city and State of New York, have invented an Improvement in Dispensers for Napkins and the like, of which the following is a specification.

This invention relates to a dispenser for napkins and like articles, and while the devices made in accordance therewith are particularly adapted for dispensing table napkins the use thereof is not so limited, inasmuch as, for example, they may be employed for dispensing paper towels or sheets of paper for any desired use. Heretofore various forms of containers or holders for paper napkins, towels and similar articles, have been employed, but in the use of the same it has been possible for the user to take one, two, or more articles as he may see fit in helping himself thereto. This obviously results in an unnecessary waste and consequent additional expense to the proprietor who supplies the napkins or towels or similar articles for his patrons. Heretofore various forms of containers or holders for paper napkins, towels and similar articles have been supplied to discharge individual units of such articles, that is to discharge the articles one by one, but all these devices required more or less complicated folding, arranging and placing of the said articles, in order to obtain the desired possibility of individual discharge.

The object of my present invention is to provide a dispenser of simple construction which requires a folding machine and napkin arrangement of less complication and expense than those heretofore used. The form of the device made in accordance with my invention is particularly adapted to dispense napkins folded in a rectangular form and placed in a superimposed pile in which the edges of the napkins are in alignment with each other and are so maintained in position that corresponding edges of the outermost sheets are separated so as to make them available to be grasped by the hand of the user and withdrawn from the dispenser one at a time, as will be hereinafter more particularly described.

In the drawing:

Fig. 1 is a longitudinal section illustrating a dispenser made in accordance with my present invention.

Fig. 2 is a plan of the same.

Fig. 3 is an enlarged partial cross section illustrating the manner in which the corresponding ends of the outermost sheets are separated for facilitating the removal of the same one at a time from the apparatus.

Fig. 4 is a longitudinal section illustrating another form of the invention.

Fig. 5 is a plan of the construction of the dispenser as shown in Fig. 4.

Fig. 6 is a longitudinal section of another form of the invention.

Fig. 7 is a plan of the same, and

Fig. 8 is a diagrammatic elevation illustrating the advantage in the use of the dispenser made in accordance with this invention.

Referring to the drawing and particularly to Figs. 1, 2 and 3 in which I have illustrated the preferred form of the invention so far as I am at present aware, it will be seen that the dispenser may be made to comprise a base 10 and a standard 11 extending therefrom in order that the apparatus may be placed on a table, counter or similar support to be readily accessible in use. At the upper end the standard is provided with a head 12, and intermediate the base and the head 12 the standard may furthermore be provided with longitudinal ribs indicated at 13. It will be noted that in the form of the invention the face of the head 12 is made at an inclination to the horizontal. This head is adapted to be connected to a support plate 14 by means of screws 15 or otherwise in such a manner that the face of the support is at substantially the same inclination to the horizontal as the face of the head. Extending from the support plate 14 I employ a plurality of posts. The support plate is preferably rectangular in configuration, although not so limited, and one of the posts as indicated at 16 is placed in a central position longitudinally of the plate 100 and is adapted to serve as a stop and a guide post for the napkins or towels when placed on the support plate, as hereinafter described. Adjacent the longitudinal edges of the support plate the other sets of posts as indicated at 17 and 18 are suitably secured, these

posts also acting to guide and determine the position of the napkins or towels when placed on the support plate. It will be understood that the posts 16, 17 and 18, may 5 be employed in any desired number and set in any suitable arrangement, and also that they may be connected to the support plate in any manner whatsoever so that they will extend therefrom in positions parallel to 10 the standard when the same is adapted to stand in a vertical position so that the posts are also vertical; or if the standard is adapted to assume any other than a vertical position in use the posts are so placed in the 15 support plate that each one when in use will assume a vertical position.

I also employ a member which may be termed a floating cover comprising a top 19 which conforms in outline with the support 20 plate 14 and is of appreciably larger dimensions, together with end walls 20 and 21 and side walls 22 and 23. The top plate 19 is provided with a plurality of openings, there being an opening for each of the posts 25 16, 17 and 18, each hole being of the same configuration as the cross section of these posts so that the posts also serve as guides for the floating cover. It will be noted in this figure of the drawing that the cover 30 is so made that in conjunction with the support plate it assumes a rhomboid shape in cross section. At the upper edge of the floating cover or that at which the angle is acute between the top plate 19 and the 35 end wall 21 there is a slot or opening 24. This slot extends an appreciable distance into the top plate 19 and a relatively smaller distance into the end plate 21 and also extends across the top plate sufficiently far to 40 be a length approximately equal to the width of the napkins or towels adapted to be placed in the dispenser.

In the use of the device hereinbefore described, the floating cover may be removed 45 and a bundle of napkins 25, for example, placed upon the support plate, it being understood that the side posts 17 and 18 act as guides to position the napkins longitudinally which are folded to a form 50 to conform to the configuration of the support plate and that the post 16 acts as a guide and a stop for the same. The floating cover is then replaced and by the action of gravity presses upon the superimposed 55 napkins to maintain the same in position. The weight of the floating cover also causes the greater portions of the underlying napkins to be evenly compressed beneath the same. At the upper edges, however, of the 60 napkins or sheets due to the configuration of the slot or opening 24 the pressure is reduced along the edges of the outermost napkins causing the same to slightly separate, it being understood that the ex-

tent of the slot in the end wall 21 is sufficient or approximately so to merely make it possible to grasp the edge of the outermost, in this instance the uppermost napkin, and to then withdraw the same from the dispenser, it being understood that when the outermost napkin is thus withdrawn the next succeeding napkin takes its place and in like manner may be withdrawn from the device.

Referring to Figs. 4 and 5, in which another form of the invention is illustrated, it will be seen that I may employ a casing or container including a base or bottom wall 27 and suitable side walls 28, the container being normally open at the top. The bottom or base 27 is adapted to assume an inclined position when the container is affixed to a suitable support, as for example, a pillar or a side wall. Extending from the bottom wall 27 are guide posts 29 and 30. 75 These are so placed as to assume an upright or vertical position when the dispenser is fixed in place for use and serve as means for positioning the pile of superimposed napkins or other similar sheets of paper or other like material and also to act as guides for a cover member 31 adapted to rest upon the superimposed pile of napkins or sheets to maintain the same in position in the container. In this instance the forward edge 80 of the bottom wall and the adjacent portions of the end wall are slotted as indicated at 32 for the same purpose as the slot 24 provided in the floating cover in the preferred form of the invention as hereinbefore described.

Or as shown in Figs. 6 and 7, for example, the dispenser may consist of a container 33 mounted on a suitable support 34 and fitted with a cover 35 which, when in place, 105 remains in position. In this instance, also, the bottom wall of the container is preferably inclined and fitted with posts 36 and 37 acting as guides and spacers for the weight 38 and the superimposed pile of napkins or other paper articles placed in the container and adapted to be dispensed therefrom one at a time through the slot 39 which, in this instance, is in the lower forward corner like the corresponding opening 110 in the form of the invention shown in Figs. 4 and 5.

It will now be apparent that in the device as illustrated, as well as in other equivalent forms of devices in which my present 120 invention may be incorporated, the napkins, towels or other articles of paper or similar material are placed upon the support plate in a superimposed pile and maintained in position by the floating cover or equivalent 125 device which is guided upon the posts and exerts a substantially even pressure against the underlying superimposed pile of nap-

kins or other articles. The pressure thus exerted is substantially equal over the area of the napkins except at the end or side of the dispenser from which they are adapted to be drawn. In view of the inclination of the napkins and the slotted feature of the floating covering or its equivalent structure the pressure at one end and along one edge of the outermost napkins or sheets whether 5 they are uppermost or lowermost is relieved or lessened and causes this edge of the outermost napkins to bulge or to be separated causing the end of the outermost napkin to extend through or partially through the 10 slot or opening in order that it may be readily grasped and withdrawn from the dispenser, the slot being so formed in any instance that it is substantially impossible to grasp and withdraw more than one napkin at a time from the dispenser.

In all of the forms of the invention as herein shown and described the devices are rectangular in plan, being adapted to accommodate napkins or other similar paper 25 articles folded to this form. It will be understood, however, that the invention is not limited to devices which are rectangular in plan as paper articles may be folded to other configurations and the plan of the 30 dispenser made to accommodate the same without departing from the nature and spirit of the invention.

It will be readily apparent that in the use 35 of a dispenser for paper napkins and the like in which a horizontal support is employed the exposed thickness of the pile of napkins at the end thereof from which the outermost napkins are to be withdrawn is the same thickness of the pile of folded 40 napkins. It will therefore be apparent that employing a dispenser in which the support for the pile of napkins or other similar articles is placed at an inclination the thickness of the exposed end of the pile of napkins from which the uppermost napkins are 45 to be withdrawn is increased thereby facilitating the individual withdrawal of the upper or outermost napkin. For example as indicated in Fig. 8 the thickness of the 50 exposed end of the pile of napkins increases in a proportion that is dependent on the angle of the inclination of the base to the vertical. As shown in this figure of the drawing if E represents the thickness of the 55 exposed end of the pile of napkins, T the normal thickness of the pile, and α the angle to the vertical at which the support is

placed, then $E = \frac{T}{\cos \alpha}$. Consequently the

edge of the pile at which the sheets or napkins are withdrawn is greater than the thickness of the pile. The sheets or napkins at this end overlap each other appreciably 60 and consequently facilitate the grasping of

the uppermost napkin and withdrawing it individually from the pile.

I claim as my invention:

1. In a device for dispensing sheets of paper and like material, an inclined base 70 adapted to support a pile of superimposed sheets placed thereon, and a cover device adapted to extend over and to rest upon the top of the said superimposed pile of sheets, and having an opening therein whereby a portion of the outermost sheet adjacent the 75 said opening in the cover is caused to separate from the next adjacent sheet, thereby facilitating the withdrawal of the outermost sheet from the superimposed pile thereof. 80

2. In a device for dispensing sheets of paper and like material, an inclined base, spacer members, fixed in and extending from the said base for positioning a pile of superimposed sheets placed on the said base, 85 and a cover device adapted to extend over and to rest upon the top of the said superimposed pile of sheets, except at one end thereof, where the said cover device is provided with a recess to cause the end portion 90 of the outermost sheet to separate from the adjacent portion of the next succeeding sheet, thereby facilitating the withdrawal of the outermost sheet from the superimposed pile thereof. 95

3. A device for dispensing paper sheets and the like, an inclined integral base, spacer members fixed in and extending from the inclined base for positioning a pile of superimposed sheets placed on the said base, and a cover device adapted to extend entirely over, and to rest upon the top of the said superimposed pile of sheets, to be movable on the said spacer members 100 for exerting a pressure on the superimposed pile of sheets, the said cover member having an opening therein, adjacent one end thereof, for causing the adjacent portion of an end of the uppermost sheet to separate from the adjacent end of the next succeeding 105 sheet to facilitate the withdrawal of the uppermost sheet from the superimposed pile thereof. 110

4. In a device for dispensing paper sheets and the like, an inclined integral base, spacer members, fixed in and extending from the said base for positioning a pile of superimposed paper sheets placed on the said base, and a cover device adapted to extend entirely over and to rest upon the top of the said pile of superimposed sheets, to be guided by the said spacer members to exert a substantially uniform pressure over the entire surface of the said pile of superimposed sheets, except at one end thereof, 115 where the said cover device is recessed to relieve the pressure and to cause the adjacent edge portion of the uppermost sheet to separate appreciably from the next succeeding sheet thereof, necessitating the 120 125 130 135

withdrawal of the uppermost sheet from the superimposed pile thereof.

5. In a device for dispensing paper sheets and the like, an inclined integral base, posts all fixed in and extending from the said base for positioning a pile of superimposed sheets placed thereon, and a cover member adapted to extend entirely over and to rest upon the top of the said superimposed pile 10 of sheets and having an opening at one end thereof producing a lessened pressure beneath the opening than beneath other portions thereof causing the corresponding end portion of the uppermost sheet to separate 15 from the adjacent portion of the next succeeding sheet thereby facilitating the withdrawal of the uppermost sheet from the superimposed pile thereof.

20. In a device for dispensing paper sheets and the like, an inclined support, posts extending from the said support for positioning a pile of paper sheets placed on the said support, and a cover comprising top and side walls adapted to enclose a pile of superimposed sheets placed upon the said support and provided with an opening at one end for lessening the pressure on corresponding end portions of outermost sheets permitting the same to separate and thereby facilitating the withdrawal of one sheet 25 at a time from the device.

25. In a device for dispensing paper sheets and the like, an inclined support, posts extending from the said support for positioning a pile of paper sheets placed on the said support, and a cover comprising top 30

and side walls and adapted to enclose a pile of sheets placed upon the said support, there being openings in the top plate through which the said posts pass in order 40 that the posts may act as guides for the said cover, the said cover fitting over the support and provided in one end with a slot extending appreciably in the top plate and slightly in the adjacent end wall for reducing the pressure on the end portions of the outermost sheets causing the same to separate and thereby facilitate the withdrawal of one sheet at a time from the device. 50

8. In a device for dispensing paper sheets and the like, an inclined support, a series of posts connected to and extending from the said inclined support for positioning a pile of superimposed paper sheets thereon, and a cover comprising top and side walls adapted to enclose the superimposed pile of sheets and to be guided by the said posts to exert a pressure upon the said pile of sheets, the cover being provided with a recess extending an appreciable distance in the top member and a slight distance in the adjacent end wall to decrease the pressure beneath the opening to cause the edge portions of the underlying sheets to bulge or separate thereby permitting the outermost sheet to be easily grasped and withdrawn 55 from the device. 60 65

Signed by me this 31st day of March, 1923.

GEORGE G. ERDOS.
